Patented Apr. 30, 1957

180,174

AIR DRYER

Louis E. Beyer, Chicago, Ill., assignor to Electric-Aire
Engineering Corporation, a corporation of Illinois

Application December 14, 1955, Serial No. 39,334

Term of patent 14 years

(Cl. D49—1)

Fig. 1.

*Fig. 2.**Fig. 3.*Figure 1 is a side elevational view of an air dryer embodying the new design;

Figure 2 is a top plan view thereof; and

Figure 3 is an end view thereof.

The end not shown is identical with that shown in Figure 3, and the side not shown is plain.

I claim:

The ornamental design for an air dryer, as shown and described.
